PIPE CUTTER

Cicero C. Brown and Jaros J. Hastik, Houston,
Tex., assignors to Brown Oil Tools, Inc., Houston,
Tex., a corporation of Texas

Application June 5, 1941, Serial No. 396,724

15 Claims. (Cl. 164—0.7)

This invention relates to pipe cutters and has for its general object the provision of a pipe cutter which may be more easily manufactured and which will be more efficient in use than those heretofore devised.

The particular class of pipe cutters to which this invention relates is adapted to be run into a well or other hole for the purpose of cutting a pipe located therein. Cutters for this purpose have been designed in the past and such cutters have included means for anchoring the cutter body within the pipe to be severed and cutting means adapted to move outwardly and sever the pipe upon rotation and other manipulation of the tool.

It is an object of this invention to provide a novel and highly effective means for anchoring a portion of such a cutter assembly against longitudinal movement within the pipe to be severed while the severing operation is being carried on.

A further object of this invention is to provide a readily releasable latching means whereby the anchoring portion of the device may be held inoperative until it is desired to anchor the cutter in the pipe to be severed, and which may after the severing operation or at any other time when desired be moved quickly into position to again hold the anchoring means in inoperative position.

Another object of this invention is to provide such a latching means for the anchoring device which will not stick in either position, which will be simpler to manufacture, which will possess a smaller number of parts than any heretofore known, which may be inserted or removed as a unit so that it may be easily replaced or repaired whenever desired without danger of dropping small parts, and which will not become clogged by small particles of foreign matter which might get in between the working parts.

Another object of this invention is to provide a pipe cutter of the type referred to in which expanding means for the respective knives of the cutter may be individually inserted or removed without need for disassembling the remainder of the tool.

It is a further object to provide such a device in which the cutter expanding means for each knife will be independent of the expanding means for the other knives of the device.

Another object of this invention is to provide such a device in which portions of the cutter body below the knife expanding means may be made larger and stronger than is possible with previously known constructions.

Another object of this invention is to provide a device in which the usual possible movements of the device as it is being lowered into a hole will tend to keep the anchoring means latched in released position.

One other object of this invention is to provide anchoring slips for such a cutting device and to provide a mounting therefor which will hold said slips positively and securely in whatever position may be desired by the operator, thus preventing their loss in the hole.

Other objects and advantages of this invention will become apparent from the following description taken in connection with the accompanying drawings wherein is set forth by way of illustration one embodiment of the invention.

In the drawings:

Fig. 1 is a view partly in side elevation and partly in vertical cross section showing the upper portion of a cutting tool constructed in accordance with this invention;

Fig. 2 is a similar view showing the lower portion of the same tool and forming a continuation of the lower end of Fig. 1;

Figs. 3, 4, 5 and 6 respectively are transverse cross sections taken along the lines 3—3, 4—4, 5—5, and 6—6 of Fig. 1;

Figs. 7, 8, 9 and 10 are similar transverse cross sections taken along the lines 7—7, 8—8, 9—9, and 10—10 of Fig. 2;

Fig. 11 is a view generally similar to Fig. 1 but illustrating the device inside a pipe which has just been severed by the tool, the cutter knives being shown in expanded position;

Fig. 12 is a continuation of the lower portion of Fig. 11 illustrating the lower end of the same device within the pipe that has just been severed;

Fig. 13 is a transverse cross section taken along the line 13—13 of Fig. 12;

Fig. 14 is a fragmentary view showing a portion of the device illustrated in Figs. 1 to 13 inclusive within a pipe to be severed and showing in elevation the anchoring means for the cutting device.

Fig. 15 is a side elevation of the cage for holding the gripping dogs forming a part of the latching assembly for the anchoring portion of this device;

Fig. 16 is a top plan view of the element shown in Fig. 15;

Fig. 17 is a view on a reduced scale similar to Figs. 11 and 12 showing the pipe cutter of this invention just after it has severed a pipe and before the knives have been retracted.

The tool illustrated in the drawings has a main body portion 1 which is threaded or otherwise formed at its upper end to receive the lower end of a tool joint 2 or other connection, the same being in turn mounted on the lower end of the pipe for operating the pipe cutter. Adjacent its upper end this body member 1 is formed with a plurality of slots 3 which extend longitudinally with respect to the body and which are spaced circumferentially from each other. About the body and overlying the upper ends of these slots there is welded or otherwise secured a split sleeve 4, thus forming a downwardly open socket 5 at the upper end of each of these slots. Disposed within each of the sockets 5 is a slideable wedge block 6 urged downwardly at all times by means of a spring 7, which is inserted into the socket ahead of the block 6.

Pivotedly mounted within each of the slots 3 below the sleeve 4 is a knife consisting of a body portion 8, a cutting point portion 9 and a tail piece 10. The tail piece 10 is disposed upwardly as shown and is adapted to be acted upon by the wedge surface of the block 6 so that under the influence of the spring 7 this block tends at all times to urge the tail portion 10 of the knife outwardly and to retract the point portion by swinging the knife about its pivot 11.

In previous constructions it was customary to make the body portion a short distance below the knives of a radius equal to or less than the distance between the bottoms of the slots and the central axis of the body so that the slots would run out of the body at the point of reduction. This was for the purpose of permitting a sleeve having integral knife expanding fingers thereon to be moved upwardly over the lower end of the body during the assembly of the tool so that the knife expanding fingers might be fitted into the slots below the knives.

In the present construction the body is in a similar manner reduced in cross section at 12 a short distance below the lower ends of the knives. However, for the purpose of retaining a sufficient thickness of material in the body member to give it the strength which is desired, the reduction is not as great as was the case in the prior constructions referred to. Instead, the body member below the point of reduction is made of sufficient diameter to give it the desired strength although of less diameter than the upper portion of the body member. The slots 3 instead of being made of the same depth throughout their length, as in the prior constructions, are made of reduced depth a short distance below the lower ends of the knives, so that they will just run out of the body at the point of reduction thereof indicated by the numeral 12.

In order to make this construction possible, the knife expanders are not made integral with a sleeve and slipped over the lower end of the cutter body as in previous constructions but are made as individual members. These individual members are in the form of fingers having wedge-shaped upper ends 13, intermediate body portions 14 and T-shaped head portions 15 on their lower ends. The wedge-shaped upper ends 13 are made of greater thickness in a radial direction than the intermediate body portions 14, so that these wedge portions will fit down into the deeper portions of the slots 3, while the intermediate body portions 14 may overlie the relatively larger reduced lower end of the body member 1 of the cutter.

These knife expanders are individually put in

place on the cutter body after a sleeve 16 has been slipped over the cutter body, and the T-heads 15 are fitted into corresponding T-slots 17 in the upper end of this sleeve. The knife expanders are then secured in place within the upper end of the sleeve 16 by means of locking pins 18 extending across the upper ends of the T-slots 17 and through openings provided for the purpose in the knife expanders 14.

10 The body of the cutting tool is still further slightly reduced in diameter at 18a to form a downwardly facing shoulder and the sleeve 16 is counterbored from its lower end to form a chamber between the inner surface of the sleeve 15 and the outer surface of the cutter body for the reception of a compression spring 19. This spring 19 is held within the sleeve 16 under a predetermined initial compression by means of a ring 20 which is welded or otherwise suitably secured within the lower end of the sleeve 16 as shown at 21. On the upper end of the spring 19 is a ring 22 which serves to prevent the spring 19 from slipping over or past the shoulder 18a on the body of the cutting tool.

25 The sleeve 16 and the parts carried thereby are keyed to the body 1 of the cutting tool by the engagement of the sleeve with the knife expanders so that this sleeve and associated parts rotate with the body 1 of the cutting tool. The lower surface of the ring 20 is provided with a friction bearing surface adapted to receive the upper end of a wedge-shaped sleeve 23, which likewise has a friction bearing surface on its upper end bearing against the first friction bearing surface at 24. This wedge-shaped ring or sleeve is limited in its upward movement with respect to the body of the cutting tool by means of an internal shoulder 25 adapted to bear against a downwardly facing shoulder 26 on the body of the cutting tool. This sleeve 23, however, is rotatably mounted on the cutting tool so that the cutting tool may rotate with respect to this sleeve. The sleeve is held in place on the body member by means of a small diameter holding sleeve 27 surrounding the body of the cutting tool below the sleeve 23 and bearing against its lower end. This sleeve 27 is in turn held in place by means of a nut 28 that bears against its lower end and is threadedly mounted on the lower end of the cutter body as shown at 29. This nut is locked against backing off by means of a set screw 30 and is preferably shaped at its lower end to form a guide 31 for the purpose of guiding the tool into the pipe to be cut.

30 35 40 45 50 55 60 65 70 75 The sleeve 23 is formed with dove-tailed ridges 32 on its outer surface as shown in Fig. 7, and these ridges are adapted to be received in corresponding grooves in the rear faces of the slips 33. These slips have downwardly directed teeth so as to anchor within a pipe to be cut and prevent downward movement of the tool.

The slips 33 may be of any number desired and have integral arms 34 extending downwardly therefrom and terminating in T-shaped heads 35. These T-shaped heads fit in corresponding T-shaped notches or slots 36 in a sleeve 37. The sleeve 37 intermediate its ends is formed with a plurality of circumferentially spaced sockets 38 adapted to receive friction shoes 39. These friction shoes 39 are normally pressed outwardly by means of springs 40 interposed behind them. They are retained within their sockets, however, by means of split rings 41 secured in place by screws 42 and extending around the exterior of the sleeve 37. The shoes 39 are provided with

extensions 43 at their ends for the purpose of engaging the inner surfaces of the split rings 41 to keep the shoes 39 in place.

The outer surfaces of the shoes 39 are formed with teeth adapted to frictionally engage a pipe to be cut to hold the sleeve 31 frictionally against rotation within such pipe. These teeth 44 extend generally speaking in a longitudinal direction with respect to the body of the cutting tool but are slightly inclined with respect to the axis of the cutting tool so that as the device is lowered through a pipe to be cut these teeth will tend to cause a slight rotation of the sleeve 31 in a right hand direction as one would look at the device from its upper end. The purpose of this will 15 presently appear.

The sleeve 31 is counterbored at its lower end to provide a chamber 45, and the lower end of this counterbore is provided with threads 46 into which is threaded a cage-like element 47 clearly illustrated in Figs. 15 and 16. This element has threads 48 adjacent its lower end for the purpose of engaging with the threads 46 in the sleeve 31 and has a flange 49 at its lower end for the purpose of limiting such engagement. At its upper end this element is formed with three prongs 50 equally spaced circumferentially, which prongs are formed on a slightly smaller diameter than the threaded portion 48 but are provided with helical grooves 51 for the purpose of receiving a helically wound wire spring.

Fitted between the prongs 50 on this element are an equal number of dogs 52. These dogs 52 are so shaped that they may move outwardly with respect to the prongs 50 but their inward movement is limited by engagement with the radial side faces of the prongs 50 as shown in Fig. 13. These dogs are formed on their outer surfaces with helical grooves corresponding in pitch to those on the prongs 50 but of such depth that they will be normally held in their innermost position by means of the helical spring 53 above referred to.

On their inner surfaces these dogs are provided with buttress type screw threads adapted to engage with similarly formed screw threads 54 on the exterior upper portion of the nut 28.

The screw threads described are all right hand screw threads.

In assembling the device above described, the 50 springs 7 and the blocks 6 are first put in place and the knives 8 are put in and secured by their pivots 11. The sleeve 16 with its associated pre-compressed spring 19 is then slipped over the lower end of the body member and when the ring 22 engages the shoulder 18a on the body member the knife expanders 14 may be put in place one by one and secured by the retaining pins 18. This will hold the sleeve 16 in position on the cutter body.

The T-heads 35 on the slips 33 are then fitted in the T-slots 36 in the sleeve 31, and the dove-tailed grooves in the inner surfaces of the slips 33 are caused to engage the tongues 32 on the expander sleeve 23. Thereupon the entire assembly, expander sleeve, slips, and sleeve 31 are slipped in place over the lower end of the cutting tool body until the upper end of the expander sleeve engages the ring 20 in the lower end of the sleeve 16. The sleeve 27 is then slipped in place to hold the expander sleeve 23 in place and the entire device is held together by placing the nut 28 in position over the lower end of the cutting tool body.

It will readily be seen that the unitary assem-

bly formed by the cage shown in Fig. 15 and the dogs 52 together with the retaining spring 53 may be engaged within the lower end of the sleeve 31 either before this sleeve is put in place or just prior to the time the nut 28 is put in place. In any event, it is secured in place before the nut 28 is engaged with the lower end of the cutting tool body. The nut 28 is then screwed home and the buttress-type threads on the exterior of this nut 10 engaging with the corresponding thread-like grooves on the inner surfaces of the dogs 52 may be forced between these dogs causing them to expand and ride over the threads on the nut. If desired, the nut may be screwed home before the dogs 52 are caused to expand, this being made possible by a mere upward movement of the sleeve 31 together with its associated parts.

Either before the sleeve 31 is put in place or afterwards, when most convenient, the shoes 39 will be put in place together with the springs 40 and will be secured in place by the split rings 41.

In operation, the dogs 52 are caused to be fully engaged with the buttress-type threads on the nut 28 before the device is inserted in the hole. 20 This will serve to hold the sleeve 31 in its lowermost position and to hold the slips 33 adjacent the lowermost end of the expander sleeve 23. As the device is lowered into the well it frequently happens that the upper end of the drill pipe or other pipe on which the cutting tool is being run may be rotated slightly to the right in the course of connecting the various joints as the pipe is inserted. In order to prevent this from causing an unscrewing of the segments 52 from the threads on the nut 28, the teeth 44 on the shoes 39 are inclined as above described. Due to this 25 inclination of these teeth there is a tendency as the device is lowered for the sleeve 31 to be turned toward the right and thus to counteract any unscrewing movement due to the slippage just referred to.

When the point in the hole has been reached where the pipe is to be severed, the string of pipe on which the tool is being run will be rotated to 30 the right. This will cause an unscrewing of the segments 52 from their engagement with the threads 54 on the nut 28. With these threads disengaged the sleeve 31 and the slips 33 may move upwardly with respect to the body of the tool, or, conversely the body of the tool may move downwardly with respect to these parts thus moving the expander sleeve 23 in between the slips 33 and expanding these slips into engagement with the pipe to be cut. Weight is now allowed 35 to be placed upon the cutter body causing the body to move downwardly with respect to the expander sleeve 23. Resting on the expander sleeve 23 is the ring 20 and the sleeve 16, and the sleeve 16 carries the knife expanders 14. Inasmuch as the spring 19 is pre-compressed a predetermined amount, there must be an equivalent weight placed 40 upon the body of the cutting tool before this spring will be further compressed and before the body of the cutting tool can be moved downwardly with respect to the ring 20 and its associated parts. When this amount of weight is placed on the body of the cutting tool, this body will begin to move downwardly and as it is moved downwardly the lower ends of the knives will 45 come against the inclined surface 13 on the upper ends of the knife expanders and will cause expansion of the knives into cutting engagement with the pipe to be severed. Rotation of the pipe cutter will now cause a severance of the pipe.

After the pipe has been severed, a mere upward

movement of the cutting tool body will cause an upward movement of the knives with respect to the inclined surfaces 13 of the knife expanders and will permit the knives to be retracted by the blocks 6 and the springs 7. Further upward movement of the cutting tool body will cause the engagement of the threads 54 on the nut 28 with the dogs 52. Due to the shape of these threads the dogs 52 will be moved outwardly against the tension of the spring 53 and the threads 54 may move upwardly between the dogs so that the segmental threads on the dogs may be engaged therewith. The sleeve 37 will now be held downwardly to hold the slips 33 in their inactive position; whereupon the cutting tool may be moved to any other position in the pipe to another cut, if desired, or may be withdrawn from the hole.

Having described our invention, we claim:

1. A pipe cutter having a body for insertion into a pipe to be cut, cutting means on the body, an anchor on said body, locking means on the body for locking the anchor in the pipe, latching means for holding said locking means in inoperative position, said latching means being releasable upon relative rotation of the body and anchor in one direction to free the locking means, and dogs carried by the anchor and having portions for engaging the inner surface of the pipe, the portions of the dogs engaging the inner surface of the pipe having elongated teeth inclined to the axis of the pipe to impart rotary motion to the anchor as the latter is introduced into the pipe in a direction opposite to that effecting release of the latching means to prevent premature release of said latching means.
2. A pipe cutter comprising a body having a plurality of circumferentially spaced longitudinally extending grooves in the surface thereof, a plurality of levers pivotally mounted in said grooves about axes transverse to the axis of the body, a cutter blade on one end of each lever, resilient means urging the levers to a position in which the cutter blades are within the periphery of the body, wedges slidably mounted in said grooves, and means spaced farther from the axis of the body than the innermost portions of said wedges for displacing said wedges between the bottoms of the grooves and the blade carrying ends of the levers to displace the blades beyond the outer periphery of the body.
3. A pipe cutter comprising a body having a plurality of circumferentially spaced longitudinally extending grooves in the surface thereof, a plurality of levers pivotally mounted in said grooves about axes transverse to the axis of the body, a cutter blade on one end of each lever, resilient means urging the levers to a position in which the cutter blades are within the periphery of the body, wedges slidably mounted in said grooves, a sleeve slidably mounted on said body and of larger internal radius than the least distance of the bottom of said groove from the axis of the body, means for anchoring the sleeve in said pipe against downward movement, and means connecting said wedges to the sleeve for displacing said wedges between the bottoms of the grooves and the blade carrying ends of the levers to displace the blades beyond the outer periphery of the body upon lowering the body into the pipe.

4. A releasable automatic latch for a pipe cutter which pipe cutter includes a body for insertion into a pipe to be cut, pipe cutting means on the body, an anchor on said body, and locking means on the anchor for locking the anchor in position

position in the pipe upon relative axial displacement of the body and anchor, said automatic latch serving to latch the body and anchor against relative axial displacement for holding the locking means in inoperative position and comprising a plurality of dogs spaced about said body and carried by said anchor, a spring encircling said dogs to hold them against said body and interengaging means on the dogs and body for latching the dogs to the body when the dogs are held against the body, said interengaging means being releasable upon relative rotation of the body and anchor.

5. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising a plurality of dogs carried by said anchor and spaced about said body, and means embracing said dogs to hold said dogs resiliently against said body, interengageable projections on said dogs and said body, one of said projections being inclined so that the other may slide thereover in one direction.

6. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising an annular cage having circumferentially spaced parts providing openings therebetween, said cage being carried by said anchor, dogs mounted between and engaged with said parts, interengageable projections on said dogs and said body, one of said projections being inclined so that the other may slide thereover in one direction, and a spring embracing said dogs to hold them together and between the parts of said cage.

7. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising an annular cage threadedly engaged with said anchor and having circumferentially spaced parts providing openings therebetween, a plurality of movable dogs carried by said cage between said parts, interengageable projections on said dogs and said body, one of said projections being inclined so that the other may slide thereover in one direction, and a spring ring embracing said dogs for resiliently holding them against said body.

8. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serv-

ing to latch the body and anchor against relative axial displacement for holding the locking means in inoperative position and comprising an annular cage secured to said anchor and having circumferentially spaced parts providing openings therebetween, a plurality of dogs carried between said parts respectively, interengageable projections on said dogs and said body, one of said projections being inclined so that the other may slide thereover, said dogs and parts having registering circumferential grooves in their outer surfaces, and a spring member lying in said grooves and extending about said dogs and parts for resiliently holding said dogs against said body.

9. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising a cage carried by the anchor and having circumferentially spaced parts providing openings therebetween, dogs between said parts respectively, interengageable projections on said dogs and said body, one of said projections being inclined so that the other may slide thereover in one direction, said parts and dogs having registering helical grooves formed in their outer surfaces, and a helical coiled spring lying in said grooves and embracing said parts and dogs to urge said dogs against said body.

10. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising an annular cage carried by said anchor and having circumferentially spaced parts providing openings therebetween, dogs between and engaged with said parts, the shape of the openings between said parts being such that said dogs cannot move inwardly from between said parts beyond a predetermined position, and a spring embracing said parts and dogs for resiliently urging said dogs inwardly against the body.

11. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising an annular cage having circumferentially spaced parts providing openings therebetween, having its exterior annular surface threaded for engagement with the threaded socket in the anchor, and hav-

ing an external radial flange remote from said parts for limiting its engagement with such anchor, dogs between said parts respectively, and spring means embracing said dogs and parts for holding said dogs in place between said parts and urging them inwardly against the body.

12. A releasable automatic latch for a pipe cutter which pipe cutter includes a body for insertion into a pipe to be cut, pipe cutting means on the body, an anchor on said body, and locking means on the anchor for locking the anchor in position in the pipe upon relative axial displacement of the body and anchor, said automatic latch serving to latch the body and anchor against relative axial displacement for holding the locking means in inoperative position and comprising a movable dog carried by said anchor, interengageable projections on said dog and said body, one of said projections being inclined so that the other may slide thereover in one direction, said projections being releasable from each other by a relative rotation of said body and anchor, and friction means on said anchor for holding it against rotation while said body is rotating to release said projections from each other, said friction means having ridges on its friction surfaces inclined with respect to the central axis of said body in a direction such that when being lowered into such opening it will tend to cause rotation of said anchor upon said body in a direction to prevent the release of said projections from each other.
13. A pipe cutter comprising a body having a recess, a cutter blade mounted within said recess for movement to retracted inactive or projected cutting positions, means for retracting said blade, means within said recess for projecting said blade to cutting position, and means radially farther from the axis of the body than the deepest part of said recess for actuating said projecting means.
14. A pipe cutter comprising a body having a recess, a cutter blade mounted within said recess for movement to retracted inactive or projected cutting positions, means for retracting said blade, means within said recess for projecting said blade to cutting position, and means for actuating said projecting means, said last means being mounted on a part of said body radially farther from the axis of said body than the deepest part of said recess.
15. A pipe cutter having a body for insertion into a pipe to be cut, cutting means on the body, an anchor on said body, locking means on the body for locking the anchor in the pipe, latching means for holding said locking means in operative position, said latching means being releasable upon relative rotation of the body and anchor in one direction to free the locking means, and friction means carried by the anchor and having portions for engaging the inner surface of the pipe, said portions engaging the inner surface of the pipe being inclined to the axis of the pipe to impart rotary motion to the anchor as the latter is introduced into the pipe in a direction opposite to that effecting release of the latching means to prevent premature release of said latching means.
